(57) **CLAIM**

The ornamental design for a radiation measuring apparatus, as shown and described.

DESCRIPTION

FIG. 1 is a front view of a radiation measuring apparatus;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a rear, right side perspective view thereof; and,

FIG. 8 is a front, right-side perspective view thereof.

The broken lines depict environmental subject matter only and form no part of the claimed design.
